(57) **CLAIM**

(**) Term: **14 Years**

The ornamental design for a medical device used for opening a glass probe and preparing a medical injection, as shown and described.

(21) Appl. No.: **29/140,531**

DESCRIPTION

(22) Filed: **Apr. 20, 2001**

FIG. 1 is a perspective view from the top and one side of a medical device used for opening a glass probe end and preparing a medical injection showing our new design; FIG. 2 is a top view of the design of FIG. 1;

(30) **Foreign Application Priority Data**

FIG. 3 is an elevational view of the one side of the design of FIG. 1;

Oct. 23, 2000 (DE) 4 00 10 286

FIG. 4 is a bottom view of the design of FIG. 1;

(51) LOC (7) Cl. **24-03**

FIG. 5 is an elevational view of an opposite side of the design of FIG. 1;

(52) U.S. Cl. **D24/133; D24/108**

FIG. 6 is an elevational view of one end of the design of FIG. 1; and,

(58) **Field of Search** D24/133, 108, D24/127, 130, 147; 604/232, 403, 415, 82, 83, 87, 414

FIG. 7 is an elevational view of an opposite end of the design of FIG. 1.
